CLAIM

The ornamental design for a cooler, as shown and described.

DESCRIPTION

FIG. 1: is a top, front, and left side perspective view of a cooler showing my new design;

FIG. 2: is a top perspective view thereof, shown with the lid open;

FIG. 3: is a cross-sectional view thereof, taken along the line 3-3 in FIG. 9;

FIG. 4: is a front elevational view thereof;

FIG. 5: is a front elevational view thereof, shown with the lid open;

FIG. 6: is a rear elevational view thereof;

FIG. 7: is a rear elevational view thereof, shown with the lid open;

FIG. 8: is a side elevational view thereof, the opposite side being a mirror image;

FIG. 9: is a top view thereof; and,

FIG. 10: is a bottom view thereof.

The broken lines in the figures illustrate the portions of the cooler that form no part of the claimed design.
